United States Patent Office.

THOMAS W. F. SMITEN, OF BROOKLYN, NEW YORK.

Letters Patent No. 81,835, dated September 1, 1868.

BREAST-PIN FASTENING.

The Schedule referred to in these Letters Patent and making part of the same.

TO ALL WHOM IT MAY CONCERN:

Be it known that I, THOMAS W. F. SMITEN, of the city of Brooklyn, in the county of Kings, and State of New York, have invented a certain new and useful Improvement in Breast-Pins, Brooches, &c.; and I do hereby declare that the following is a full and correct description thereof, reference being had to the accompanying drawings, and to the letters of reference thereon.

In breast-pins and brooches, as commonly made, the rivet-pin at the joint, between the tongue and body of the breast-pin or brooch, becomes loose by wear and falls out, thereby detaching the body of the pin from the tongue, and thus many pins are lost. Breast-pins and brooches are so frequently lost from this cause that a guard-chain and additional pin are frequently attached to them for safety; but this is a considerable additional expense, besides the trouble of fastening the two pins, and the inconvenience of the dangling guard-chain, the use of which is also objected to by many to whom it is distasteful.

The nature of my invention consists in combining, with the body of a breast-pin or brooch and the tongue, at the joint, a guard, consisting of a loop of wire or plate-metal fastened to the body of the pin, at or near the joint, and embracing the tongue near the joint closely enough to prevent it from escaping, and at the same time loosely enough to allow the tongue to work freely, thereby securing the tongue to the body of the breast-pin or brooch in case the rivet-pin should work out.

But in order to more particularly describe my invention, I will refer to the accompanying drawings, of which—

Figure 1 is a plan view of a brooch with my improvement.

Figure 2, a side view of the same.

Figures 3 and 4, plan view and section, showing the operation of the guard in securing the breast-pin when the rivet-pin is removed.

The drawings show the body *a* of the breast-pin or brooch, with a tongue, *b*, jointed to it in the usual way; that is, a small plate is soldered to the end of the tongue, and underneath it is soldered a short section of a tube or pipe, *c*, corresponding in size with the two opposite short sections of piping or tubing *d d*, soldered to the body of the breast-pin, so that a hinge-joint is made between the body and tongue by means of a rivet-pin passing through the three short tubes.

The tongue, being enlarged at the joint by the attachment of the plate and tube constituting its portion of the hinge, is confined to the body, whenever the rivet-pin falls out, by my improved guard or bridle, which may be merely a bent loop of wire, *e*, of the form shown in the drawings, embracing the tongue near the joint, and fastened by soldering the ends to the body of the breast-pin or brooch, or to that part of the hinged joint which is fast to the body. When the breast-pin or brooch is fastened in a shirt-front, or other article of dress, the loops of the guard, being smaller than the joint-end of the tongue, prevent the brooch or breast-pin from escaping from the tongue when the rivet-pin of the joint comes out.

The guard or bridle may be made a part of the joint before it is soldered on the pin, or it may be attached afterwards, and formed either of wire or pierced plate-metal. To open-back settings it may be attached by extending the ends of the loop, guard, or bridle to either side, and soldering them.

The advantages of my invention are, first, that brooches provided with it may be worn without a safety-pin and chain, as it is impossible for a brooch to be lost in consequence of the rivet falling out; second, the loop-guard acts as a check above the joint, relieving the joint from strain, and protecting it from being broken off; third, it prevents the joint from wearing loose, as it stops to a great extent the lateral play.

I claim as of my invention and improvement in breast-pins, brooches, and similar articles—

A guard or bridle, embracing the tongue near the joint, in combination with the body and tongue, substantially as described, whereby the breast-pin or brooch is securely held, and prevented from being lost by the wearer, should the rivet-pin of the joint come out.

THOS. W. F. SMITEN.
